UNITED STATES PATENT OFFICE.

GISBERT HENNESSEN AND PETER SPIX, OF MÜNCHEN-GLADBACH,
GERMANY.

MACHINE FOR FIGURING ENDLESS GLAZED PAPER.

SPECIFICATION forming part of Letters Patent No. 789,091, dated May 2, 1905.

Application filed January 12, 1905. Serial No. 240,827.

To all whom it may concern:

Be it known that we, GISBERT HENNESSEN and PETER SPIX, subjects of the German Emperor, and residents of München-Gladbach, Germany, have invented certain new and useful Improvements in Machines for Figuring Endless Glazed Paper, of which the following is a specification.

The present invention relates to a machine for figuring so-called "endless" paper—such as stained paper, wall-paper, and so on—which was hitherto glazed over the whole surface without any interruption, in a new and such a manner that only certain parts will be glazed, while the other parts remain dull, so that different designs of any kind can be produced on the surface of the paper merely by the difference between the glazed and dull parts.

The essential and new feature of the machine consists therein that a rotating roller *a*, provided with the engraved or cut design, keeps on to press the design again and again into the elastic circumference of a second roller *b* of a yielding material, which works together with a friction-roller *c*. The paper *d* or other material to be figured is passed through between the elastic roller *b*, which carries on its circumference the impressed design, and the friction-roller *c* in such a manner that that side of the paper which is to be figured is turned toward the friction-roller. By the friction of the latter the surface of the paper touching the raised parts of the design is made smooth and glossy, while the other parts remain dull, so that the design will appear on the paper through the difference between glossy and dull parts. By the action of the friction-roller the design impressed into the circumference of the roller *b* is effaced; but by the design-roller *a* it is constantly renewed. As the paper during this treatment lies upon an elastic support, it cannot possibly get torn, and the rollers are not liable to wear out soon.

Experiments have shown that it is not possible 45 to work with the machine if the roller *b* is made of metal and is provided itself with the engraved or cut design, for in that case the design-roller *b*, as well as the friction-roller *c*, would get worn out by the friction within a 50 short time and also the paper would be subjected to a great strain and be easily torn.

The roller *b*, on a part of whose elastic surface the design is only impressed, may be of any suitable material, such as paper, cotton, 55 asbestos, india-rubber, leather, and the like. The figured part of the circumference of the roller shown in the drawing is marked with little strokes.

The rollers *a* and *b* rotate with an equal 60 circumferential velocity, while the friction-roller *c* possesses a greater circumferential velocity.

The paper or other material to be figured is wound off from a roller *e*, is figured in the 65 machine, and then wound in a figured state upon a roller *f*.

The same machine can of course be used for figuring stuff of any kind.

What we claim as our invention, and desire 70 to secure by United States Letters Patent, is—

In a machine for figuring glazed paper and the like, a roller *a* provided with the engraved design, a roller *b* having an elastic circumference engaging with the roller *a* so as to receive said design on the elastic circumference, and a friction-roller *c* engaging with the roller *b*, said rollers *b* and *c* receiving the paper between them.

In testimony whereof we have signed our 80 names to this specification in the presence of two subscribing witnesses.

GISBERT HENNESSEN.
PETER SPIX.
